Patented Feb. 13, 1917.

UNITED STATES PATENT OFFICE.

EDWARD H. BANCROFT, OF BROOKLYN, NEW YORK.

BOOK-REST.

1,216,048.

Specification of Letters Patent. Patented Feb. 13, 1917.

Application filed February 25, 1916. Serial No. 80,324.

To all whom it may concern:

Be it known that I, EDWARD H. BANCROFT, a citizen of the United States, and a resident of the borough of Brooklyn, in the county 5 of Kings, city and State of New York, have invented certain new and useful Improvements in Book-Rests, of which the following is a specification.

My invention relates to improvements in 10 book-rests, and refers particularly to a device of this character adapted to prevent unnecessary strain upon the eyes of the user.

One object of my invention is a book-rest 15 adapted to hold a book, or similar object, at any desired angle to, or any distance from, the table or desk upon which it is mounted.

Another object of my invention is a book-rest which can be readily and quickly 20 adapted to hold or retain a book of any thickness.

Another object of my invention is a book-rest, whereby the leaves of a book, resting thereon, may be readily and quickly turned 25 without raising or removing the book.

Another object of my invention is a book-rest in which the proper postural position 30 of the user may be assumed and retained, while employing the natural and proper visual angle to the book or similar object held by my device.

Other objects of my invention will be evident upon a consideration of my specification and accompanying drawings.

35 It is frequently essential that a book, drawing board, or similar object, should be held in a fixed position for consultation or use, without the assistance of the user, as in the case of copying or transcribing the contents of a book, or in making drawings, paintings, sketches, &c., and in order that this may be accomplished without undue strain upon the eyes it is necessary that the angle of the book, or other object, be in the 40 correct position as to the position of the eyes of the user.

It is evident from the many uses to which 45 such objects are employed, that there is no general or universal position which will be properly applicable to all cases, and that it is necessary, therefore, that the object must be placed to agree with the peculiar circumstances surrounding each use.

50 It is further evident that two essential elements enter into the proper solution of the problem, the angle of the book with re-

spect to the surface upon which the operator is working, and its height therefrom, while in the case of drawing boards, the position of the artist must be considered.

60

It is therefore necessary that a book-rest to meet these requirements must have a vertical movement and a pivotal movement, that both of these two positions must be readily changed to meet the individual need 65 and must be capable of rigid retention, and must be capable of holding books and objects of various thicknesses.

65

My invention accomplishes all of these requirements in a simple, economical and effective manner, and its use allows the retention of a book, or similar object, in any position of visual requirement, thus causing the prevention of eye-strain with its accompanying disorders. It is adapted to inclined or horizontal surfaces, and may be readily attached 70 to the arm of a chair by any well-known means.

70

One form of my device is illustrated in the accompanying drawings, in which similar 75 parts are designated by similar numerals.

75

In the drawings:

Figure 1 shows a cross-section through the line 1—1 of Fig. 2.

Fig. 2 shows a plan view in the direction 80 of the lines 2—2 of Fig. 1, partly broken away.

Fig. 3 shows a cross-section through the line 3—3 of Fig. 1.

Fig. 4 shows a cross-section through the 85 line 4—4 of Fig. 1, the leaf-retaining members being removed.

The two side frame members 5, 5 are connected at their upper portions by the top member 6, and are each pivotally attached to the bottom connecting member 7 by means of the hinges 8, 8. The bottom connecting member 7 connects the two side bottom members 9, 9 at one end, the other end of the two side bottom members 9, 9 being connected 90 by the member 10, the whole acting as a bottom or rest for my device, to allow of its being upheld upon a horizontal surface such as a table or desk 11. Pivotally attached to the under side of each of the members 5, 5 by means of the hinges 12, 12 are supporting members 13, 13, pointed or chamfered at their lower ends to fit within the notches 14, 14 upon the upper sides of the members 9, 9 to support the frame 5, 5, 6, 7 at any 95 desired angle with respect to the horizontal surface 11. The hinges 8 and 12 are so situ- 100

105

110

ated, and the members 5. 5 and 13. 13 are of such lengths, with respect to each other, that the members 13. 13 may be folded under the members 5. 5 and the frame 5. 5. 6. 7 may be folded downwardly to rest upon the bottom members 9. 9, thus causing a compact package for shipment or storage.

A series of arms 15. 15 are pivotally attached at 16. 16 to the bottom connecting member 7, so that they may be revolved above the bottom of the device when it is desired to place it upon a flat surface at a distance from the edge thereof, or may be revolved to a position in which they extend below the bottom of the device. When the arms 15. 15 are in this last-mentioned position, the device may be placed upon a table or desk with the arms 15. 15 extending downwardly and abutting against the edge of the table or desk, thus preventing the accidental displacement of the device. Situated upon the inner surfaces of the frame members 5. 5, and extending slightly over the front and rear surfaces thereof, is a metallic member 17. 17, of channel shape and attached thereto by means of the screws 18. 18. The members 17. 17 have a series of holes 19. 19, in alinement with corresponding holes within the members 5. 5, the holes upon one member 5 being in alinement with the corresponding holes in the other member 5. The object of the metallic members 17. 17 is to prevent undue wear upon the members 5. 5.

A book supporting carriage is movably mounted to the frame 5. 5. 6. 7. This carriage comprises two tubular members 21. 21, within each of which is a slidable pin 22 of such a size and shape as to allow of entrance into the holes 19. 19 and retention therein. Each of the pins 22. 22, has a collar 23 fixedly attached thereto a distance from the outer end of the pin 22 and slidable within the tubular member 21. The inner end of each pin 22 extends through an opening in the tubular member 21, and has fixedly attached thereto the collar 24, with a finger catch 25. A helical resilient spring 26, surrounds the pin 22 and abuts upon the collar 23 and the member 36 which is fixedly attached to the member 21. A curved metallic member 27, supported upon the tubular members 21. 21, has its lower portion 28 extended outwardly at a right angle to the frame members 5. 5 and carries an elongated opening 29 for purposes to be described later.

Movably mounted upon the extended member 28, are devices for retaining the leaves of a book in open position, comprising the bottom member 30, the top 31, and the rotatable finger 32, fixedly attached to a square shaft 33, and the resilient spring 34, so situated that it will retain the finger 32 in either a horizontal or perpendicular position by its pressure upon a flat surface of the

shaft 33. The set screw 35, allows of the inward and outward movement of the leaf retaining device upon the extended member 28, and retention in any desired position thereon.

The operation of the device is as follows: The frame is supported at any desired angle for proper sight by means of the members 13. 13, the book carriage is then raised or lowered to its desired position by pressing the two finger catches 25. 25 toward each other, thus releasing the pins 22. 22 from the holes 19. 19, and allowing free movement of the carriage. When it has been situated in its desired height the pins 22. 22 are inserted into the holes 19. 19 by releasing the finger catches 25. 25. The leaf retaining members 32. 32 are then placed in a horizontal position, the book placed upright upon the carriage member 31, the back of the book resting upon the frame, and the member 31, with its attached parts slidably moved forward and backward until suited for the thickness of the particular book, and locked by means of the set screw 35. The leaf retainers 32. 32 are then raised to a vertical position, thus retaining the book in an open position. It is evident that by this device the book need not be raised or removed when it is desired to turn a leaf, as this can be accomplished by lowering the leaf retainers 32. 32, turning the leaf and raising the leaf retainers 32. 32 to an upright position.

I do not limit myself to the number, size, shape or arrangement of parts as shown, all of which may be varied without going beyond the scope of my invention as described and claimed.

What is claimed, is:

1. In a device of the character specified, in combination, a base, a frame pivotally attached to the base, means upon the two upright sides of the frame for supporting a book-carrying member and in alinement with each other, a book-carrying member slidable upon the frame, said book-carrying member carrying spring pressed means for maintaining it upon the supporting means upon the frame and for releasing it therefrom; allowing slidable movement thereof, said member being maintained upon the frame when the spring is in normal position; a member upon the book-carrying member for retaining a superimposed book in open position; and a member for maintaining the frame at any desired angle of position with respect to the base.

2. In a device of the character specified, in combination, a base, a frame pivotally attached to the base, holes within the two upright sides of the frame and in alinement with each other, a book-carrying member within the frame and slidable therein, said book-carrying member carrying pins capa-

ble of movable placement within the holes of the frame to maintain the book-carrying member at any desired position therein, and spring means for placing the pins within 5 said holes and allowing their removal therefrom, said pins being maintained within the holes when the spring is in its normal condition, said book-carrying member carrying a member for retaining a superimposed book in open position, and a member

10 for maintaining the frame at any desired angle of position with respect to the base.

Signed at New York city, in the county and State of New York, this 23rd day of February 1916.

EDWARD H. BANCROFT.
